UNITED STATES PATENT OFFICE.

JOSEPH C. FORD, OF MADISON, WISCONSIN, ASSIGNOR TO FRENCH BATTERY & CARBON COMPANY, OF MADISON, WISCONSIN, A CORPORATION OF WISCONSIN.

HAND-LAMP.

1,324,547.

Specification of Letters Patent.

Patented Dec. 9, 1919.

Application filed June 6, 1919. Serial No. 302,094.

To all whom it may concern:

Be it known that I, JOSEPH C. FORD, a citizen of the United States, residing at Madison, in the county of Dane and State of Wisconsin, have invented a new and useful Improvement in Hand-Lamps, of which the following is a specification.

This invention relates particularly to electric hand-lamps; and the primary object is to provide an improved lamp of this character, having special provision for mounting the reflector and lens in an improved manner.

A further object is to provide such a construction, having provision against accidental short-circuiting of the device.

The invention is illustrated, in its preferred embodiment, in the accompanying drawing, which represents a longitudinal sectional view, the batteries employed being shown in elevation, however.

In the construction illustrated, A represents a tubular casing which may be of convenient size to be carried readily in the hand, or, if desired, in the pocket; B, a battery, here shown as comprising two dry cells B' and B'; C, a metallic reflector mounted on one end of the casing; C', a lens surmounting said reflector; D, an incandescent lamp mounted in the reflector; and E, a contact device mounted on one side of the casing and equipped with a conductor E' leading to the front end of the casing and a conductor E² leading to the base-end of the casing.

The casing A comprises a tubular body 1 of insulating material, such as fiber, which is equipped at its base end with a threaded sleeve, or ferrule, 2, upon which is secured a metal cap 3, which supports a conical metal spring 4; a combination reflector and lens supporting device 5 comprising a threaded metal sleeve 5^a secured in the front end of the casing, and a threaded metal sleeve 5^b screwed on to the projecting end of the member 5^a, the sleeves 5^a and 5^b being equipped with flanges between which the circumferential flange of the reflector and the circumferential portion of the lens are clamped, or secured; and a metal housing-sleeve 6, lined with insulation material 6^a, said housing-sleeve being screwed onto the member 5^b and insulated therefrom by the insulating member, or material, 6^a.

The sleeve 2 is fitted on the outer surface

of the base end of the tubular body A, and secured thereto by a rivet 7 which is also secured to the thin copper strip which constitutes the conductor E². Thus, it will be seen that the conductor E² is in electrical connection with the spring 4. The cells of the battery B have zinc containers, and are provided at their upper or forward ends with central electrodes 8. The bottom of the zinc container of the lower cell rests upon the spring 4, and the bottom of the upper zinc container rests upon the electrode 8 of the lower cell, so that the cells are in series. The cells are inclosed in a paste-board tube B³. The lamp is screwed into a socket with which the reflector C is provided, and the central contact of the lamp bears upon the central electrode of the upper cell. The circuit is completed through the lamp socket, the reflector, the sleeve 5^a, and the conductor E', when the contact device E is closed. In the illustration, the contact device is shown provided with a button, or slide, 9, equipped with a spring shoe 9^a, which is adapted to make contact with the lower end of the metal strip, or conductor, E'.

The metal sleeve 5^a is fitted in the upper end of the tubular casing A and secured thereto by a rivet 10 which connects the sleeve both to the casing A and the metal strip forming the conductor E'.

The sleeve 5^a is equipped at its outer end with an inturned flange 11, upon which the peripheral flange of the reflector bears. The lens C', in turn, bears against the peripheral flange of the reflector C; and the clamping ring, or sleeve 5^b, is provided with a flange 12, which bears against the outer surface of the peripheral portion of the lens.

Thus, it will be seen that the reflector and the lens are securely clamped together, it being understood that the sleeve 5^b is screwed onto the sleeve 5^a.

The hand-lamp is thus an operative device, without the use of the housing-sleeve 6. It is preferred, however, to supply the housing-sleeve 6 as a finishing sleeve; and, in practice, the sleeve 6, the ferrule 2, and the base-cap 3 are ordinarily nickel-plated, while the insulation tube 1 may be of black fiber, so that the device will present an ornamental appearance. Inasmuch as the housing-sleeve 6 is insulated from the reflector-supporting device and reflector which form

a part of the circuit, there is no danger of the hand-lamp becoming short-circuited, even though the hand-lamp be laid upon a metal plate, which would thus afford a conducting medium between the base-cap 3 and the housing-sleeve 6. It will be noted, in this connection, that the outer end of the rivet 10 is counter-sunk and free from contact with the sleeve 6.

10 The construction described is simple, thoroughly practicable, and provides a secure connection between the insulating casing 1 and the reflector and surmounting lens. As shown, the threading of the parts is accomplished by a spinning or pressing process, which adds to, rather than detracts, from the appearance of the device. However, any suitable design may be employed for making connections and giving a 15 finished appearance to the device. In the construction illustrated, the reflector-and-lens-retaining sleeve 5^b may be unscrewed from the permanently secured sleeve 5^a, to give access to the lamp bulb.

20 25 The foregoing detailed description has been given for clearness of understanding only, and no unnecessary limitation should be understood therefrom, but the appended claims should be construed as broadly as 30 permissible, in view of the prior art.

What I regard as new and desire to secure by Letters Patent is:

1. In a hand-lamp the combination of an insulating casing, a battery therein, a closure 35 for the base-end of said casing, a spring interposed between said closure and the battery and serving to establish connection with the battery, a reflector-supporting device comprising a sleeve secured to the other end 40 of the casing and a companion sleeve fitted

thereon, said sleeves being provided with flanges, a metal reflector and a lens secured between the flanges of said sleeves, a lamp mounted in said reflector and having contact with the battery, a contact device mounted 45 on said casing, conductors extending from said contact device within said casing and having electrical connection with said first-named sleeve and with said spring, and a housing-sleeve enveloping said second-named sleeve and the upper portion of said casing and insulated from said second-named sleeve.

2. In a hand-lamp, the combination of an insulating casing, a closure for the base-end 55 thereof, a battery in said casing, a contact device mounted on one side of said casing, an internal conductor leading from said contact device to the base-end of the casing and having electrical connection with the 60 base end of the battery, an internal conductor leading from said contact device to the forward end of said casing, a sleeve fitted into the forward end of said casing and in electrical connection with said last-named 65 conductor, said sleeve being provided with an extending threaded portion and an in-turned flange, a reflector having a peripheral flange bearing thereon and equipped with a lamp having electrical connection 70 with the forward end of the battery, a lens surmounting said reflector, a clamping sleeve screwed on to said first-named sleeve and having a flange engaging the outer surface of said lens, and a housing-sleeve having an insulating lining, said housing-sleeve being screwed onto said clamping sleeve and extending over the forward end-portion of the insulating casing.

JOSEPH C. FORD.
